(57) **CLAIM**

I claim the ornamental design for a dryer, as shown and described.

DESCRIPTION

FIG. 1 is a perspective view of a dryer showing my new design.

FIG. 2 is a front elevational view of the dryer of FIG. 1.

FIG. 3 is a rear elevational view of the dryer of FIGS. 1 and 2.

FIG. 4 is a bottom view of the dryer of FIGS. 1 through 3.

FIG. 5 is a left side view of the dryer of FIGS. 1 through 4, the right side view being a mirror image thereof; and,

FIG. 6 is a top view of the dryer of FIGS. 1 through 5.

1 Claim, 3 Drawing Sheets

FIG. 1

FIG. 2

FIG. 3

FIG. 4

FIG. 5

FIG. 6
